WHEEL

Filed Jan. 3, 1922

FIG. 1

FIG. 2

Inventor
Charles William Fulton,
by Robert T. Atkin,
Attorneys.

Patented Sept. 18, 1923.

UNITED STATES PATENT OFFICE.

CHARLES WILLIAM FULTON, OF BISHOPBRIGGS, NEAR GLASGOW, SCOTLAND.

WHEEL.

Application filed January 3, 1922. Serial No. 526,739.

To all whom it may concern:

Be it known that I, CHARLES WILLIAM FULTON, a subject of the King of the United Kingdom of Great Britain and Ireland, and residing at Bishopbriggs, near Glasgow, Scotland, have invented a certain new and useful Improvement in Wheels, of which the following is a specification.

The object of this invention is to provide a wheel for road vehicles and the like which will prevent the vibration set up due to inequalities of the road surface from being transmitted to the hub and the axle of the wheel.

Many previous attempts have been made to produce such a wheel but most, if not all, have proved unsuccessful over a long period of trial, due, in most cases, to the failure of the flexible medium or media employed to give the necessary condition of elasticity through over-strain of the material or fatigue.

The present invention contemplates the production of such a wheel as will overcome this difficulty by imposing upon the elastic medium or material only such stresses as will not cause it to deteriorate with continued use.

With previous attempts to produce a satisfactory wheel in which there was used as the flexible medium metal such as steel in the form of springs, the difficulty was to get sufficient length of metal to prevent the molecules from being subjected to excessive stress under working conditions.

The wheel according to the present invention is composed of two main structures, first, a portion directly connected to the hub, hereinafter referred to as the rigid portion, and, second, a portion not directly so connected, hereinafter referred to as the floating portion. The rigid portion is circular and is itself a rigid structure, that is to say, is rigid in so far as it is analogous to any ordinary wheel which itself is not constructed to give elasticity.

The floating portion when unloaded is circular but is constructed purposely with a limited stability or a certain degree of elasticity. The elasticity or flexibility of the floating portion is relied on for absorption of the inequalities of the road surface, whereby to prevent transmission of shock to the hub axle of the wheel. The floating portion may be regarded as a flexible ring. The rigid portion or wheel

proper rides on the floating portion, the load coming on the uppermost portion of the flexible ring.

In short, the invention provides a wheel riding on a flexible ring.

It is preferred to construct the floating portion of a combination of rubber with spring steel rings tempered when flat and then sprung into circular form or so as to give molecular stress under working condition always in the same direction.

The rigid portion is formed with flanges partly accommodating the floating member and terminating in inturned lips engaging corresponding bevelled surfaces on the floating member.

The flanges are preferably punched out into spokes. The lips, which bear on the floating portion, are preferably corrugated. It is preferred to make the flanges of the rigid portion of such diameter as approximately to fit all round the floating portion, just contacting under no-load conditions.

In the wheel of the present invention the metallic spring ring or rings is or are unitary with the rubber mass, whereby the tire member is maintained stable in its own plane, thus rendering it practicable to carry the tire member entirely free from contact with the sides of the flanges or other part of the central portion save where the bevelled lateral faces engage the inclined portions of the flanges, the inclination of the engaging faces being such that the frictional drag between the flanges and the tire member exceeds the frictional drag between the tire member and the road.

The invention is illustrated by way of example in the accompanying drawing in which Fig. 1 is an elevation, partly in section, and Fig. 2 a diametric section.

The wheel shown comprises two main structures, i. e., a rigid portion 1 and a floating portion 2. The rigid portion is circular and the floating portion when unloaded is also circular but is constructed with a certain degree of elasticity so as to constitute a flexible ring whereon the rigid portion rides, the load coming on the uppermost portion of the ring.

The floating portion comprises a rubber annulus to which are secured or in which are embedded spring steel rings 4 which are tempered when flat and then sprung into circular form. In the construction shown these rings are of varying widths, thus ac-

- commodating them to the outwardly tapering form of the tire member 2. Between the rigid portion 1 and the elastic floating portion or tire member 2 is a considerable space 5 permitting said elastic floating portion or tire member to yield inwardly. Formed on or secured to the portion 1 are flanges 5 terminating at their peripheries in inturned lips 6 which engage bevelled surfaces 7 on 10 the outwardly tapered tire portion 2. The flanges 5 are punched into spokes and the lips 6 are corrugated so as to provide for effective or non-slipping driving engagement between the member 1 and the member 15 2 when the wheel is used as a driving wheel. The relative measurements of the flanges and the member 2 are such that the bevelled surfaces 7 are in contact with the lips 6 when the wheel is not under load.
- 20 It will be seen that the flanges 5 and the lips 6 formed thereon afford holding elements on which hangs a resilient tire-forming structure constituted by the member 2 which is circular when unloaded but is capable of being formed under load into approximately an ellipse, freedom being afforded for further deflection under the influence of road shock. The outer inclined portions or lips 6 of the flanges 5 engage the bevelled 25 faces 7 of the outwardly tapered tire 2, so that these parts afford a driving connection between the rigid member 1 and the tire member 2, the latter being free to yield inwardly within the channel or space between 30 the innermost ring 4 and the rigid portion 1 of the wheel.
- 35 It will also be seen that the member 2 provides a spring track to which the driving effort is transmitted at the upper side by the 40 lips 6 riding thereon.

I claim:—

1. A wheel consisting of a central portion comprising a rigid body member and flanges carried by and extending radially beyond 45 said body member; and a floating elastic rubber tire member disposed between said flanges and provided with embedded steel rings of varying widths, said tire member being separated radially from said rigid body member, said flanges having corrugated peripheral portions, inturned towards each other, to engage said tire member to hold it in driving engagement with said rigid body member.
- 50 2. A wheel consisting of a central portion

comprising a rigid body member and flanges carried by and extending radially beyond said body member; and a floating elastic rubber tire member disposed between said flanges and provided with embedded steel 60 rings, said tire member being separated radially from said rigid body member, said flanges having corrugated peripheral portions, inturned towards each other, to engage said tire member to hold it in driving 65 engagement with said rigid body member, said flanges being punched out or slotted to form spokes.

3. A wheel consisting of a central portion comprising a rigid body member and flanges 70 carried by and extending radially beyond said body member, said flanges affording a channel the outer portions of said flanges being inclined inwardly towards each other, a floating elastic tire member disposed between said flanges and having bevelled faces engaged by the inclined portions of said flanges, and concentric rings of unequal diameter, the ring of greater diameter being embedded in said tire member, and a 75 ring of less diameter lining the inner face of said tire member, said tire member being circular when unloaded and being movable relatively to said channel in such wise that, when loaded, it is deformed into approximately an ellipse.

4. A wheel consisting of a central portion comprising a rigid body member and flanges carried by and extending radially beyond 80 said body member, said flanges affording a channel the outer portions of said flanges being inclined inwardly towards each other, a floating elastic tire member disposed between said flanges and having bevelled faces engaged by the inclined portions of said 85 flanges, and spring rings embedded in said tire member, said rings being of unequal width, the narrower ring being nearer the tread than the wider ring, said tire member being circular when unloaded and being 90 movable relatively to said channel in such wise that, when loaded, it is deformed into approximately an ellipse.

In testimony whereof I have signed my name to this specification in the presence of 105 two subscribing witnesses.

CHARLES WILLIAM FULTON.
